UNITED STATES PATENT OFFICE.

ADRIAN JOHN MEERSE AND ARTHUR J. DOREN, OF OGALLALA, NEBRASKA.

DESIGN FOR A ROCKING-HORSE.

54,435.

Specification for Design.

Patented Feb. 10, 1920.

Application filed June 14, 1919. Serial No. 304,360. Term of patent 14 years.

To all whom it may concern:

Be it known that we, ADRIAN JOHN MEERSE and ARTHUR J. DOREN, citizens of the United States, residing at Ogallala, in the county of Keith and State of Nebraska, have invented a new, original, and ornamental Design for a Rocking-Horse, of which the following is a specification, reference being had to the accompanying drawing, forming a part thereof.

The figure is a perspective view of a rocking horse showing our new design.

We claim:

The ornamental design for a rocking horse as shown.

ADRIAN JOHN MEERSE.
ARTHUR J. DOREN.
